United States Patent Office

Des. 215,517
Patented Sept. 30, 1969

215,517

SEWING MACHINE CARRYING CASE OR SIMILAR ARTICLE

Henry Dreyfuss, South Pasadena, Calif., assignor to The Singer Company, New York, N.Y., a corporation of
New Jersey

Filed Apr. 4, 1968, Ser. No. 11,307

Term of patent 14 years

Int. Cl. D3—99

U.S. Cl. D87—1

Fig. 1.

Fig. 3.

Fig. 2.

Fig. 4.

Fig. 5.

Fig. 6.

Fig. 7.

FIG. 1 is a perspective view of a sewing machine carrying case or similar article embodying my new design;

FIG. 2 is a front elevational view of the sewing machine carrying case or similar article shown in FIG. 1;

FIG. 3 is an end elevational view as seen from the left in FIG. 2;

FIG. 4 is a top plan view of the sewing machine carrying case or similar article shown in FIG. 2;

FIG. 5 is a rear elevational view of the sewing machine carrying case or similar article shown in FIG. 2;

FIG. 6 is an end elevational view as seen from the right in FIG. 2; and

FIG. 7 is a bottom plan view of the sewing machine carrying case or similar article shown in FIG. 2.

I claim:

The ornamental design for a sewing machine carrying case or similar article, substantially as shown.
